UNITED STATES PATENT OFFICE.

WILLIAM M. ANDERSON, OF NEW YORK MILLS, MINNESOTA.

TROUBLE LAMP FOR AUTOMOBILES.

Application filed February 8, 1923. Serial No. 617,854.

To all whom it may concern:

Be it known that I, WILLIAM M. ANDERSON, a citizen of the United States, residing at New York Mills, in the county of Otter Tail and State of Minnesota, have invented certain new and useful Improvements in Trouble Lamps for Automobiles, of which the following is a specification.

My invention relates to so-called trouble lamps for automobiles and the object is to provide a simple and efficient device which is normally used as a dash lamp but in an emergency can be extended to any part of an automobile for locating any trouble.

In the accompanying drawing:

Fig. 1 is a top view of my device with its cover shown in dotted lines.

Fig. 2 is a side view of Fig. 1 with the cover shown in section and some minor parts omitted.

Referring to the drawing by reference numerals, 3 designates the dash or instrument board of an automobile. At the inner side of said board I attach as at 4^a a socket 4 in which is held the tapered end 5^a of a tube 5 the free end of which has a downward opening through which an electric bulb 6 throws light.

The tube 5 is held in place by a finger catch 7 the front end of which has a tooth 7^a normally engaging in a notch 8 in the socket 4 and held thus by a coil spring 9 engaging the under side of the opposite end of the finger catch. The tube 5 is thus readily detachable from the socket. A cable 10 containing the two wires of the circuit furnishing current to lamp 6 is extended forward from the tapered end 5^a of the tube and is wound on a reel 11, the length of said cable being predetermined but preferably about 12 to 15 feet. Said reel is mounted on a horizontally disposed shaft 12 journaled in a light frame 13 secured on the front side of the dash 3. At one side of the reel I secure on its shaft a pinion 14 driven by a gear 15 rotated by a coil spring 16 one end of which is held by a pin 17 (see Fig. 1).

The end of the reel opposite the pinion 50 has two concentric contact rings 18-19 contacting with electrodes 20 (see Fig. 1) held rigidly in a plug 21 of the frame 13. Each wire of the cable 10 is connected to one of the contact rings 18-19 within the reel as 55 at 22-23 (see Fig. 1). Facing the outer end of plug 21 is the bottom of a cap 24

which has a vertically disposed flange 25 with two diametrically opposite slots 26 through which two studs 27, secured in the frame, project outwardly and have washers 28 and a compression coil spring 29 for each stud held in compression between the washer and the flange 25. 30^a and 30^b are two wire ends of a cable 30 connected with any suitable source of electricity (not shown). Said wire ends are inserted in apertures in the bottom of cap 24 and their inner ends so spaced that when the cap 24 is rocked the wire ends 30^a-30^b will contact with the electrodes 20, permitting current to reach the lamp 6 and return through the above mentioned rings 18-19 and the cable 10.

The cap may be oscillated by a push-and-pull switch button 31 forward of the dash and having a rod 32 extending forward of the dash and connected as at 33 to the flange 25.

34 and 35 are the top and bottom halves, respectively, of a sheet metal cover adapted to inclose that part of the device forward 80 of the dash. Their edges may overlap as at 36 (Fig. 2) and be secured to the frame 13 with a number of screws 37.

In the use of my device it will be readily understood that the dash light is normally 85 in its place on the dash or instrument board and the circuit to lamp 6 is controlled by the button 31. Should trouble develop in any part of the automobile the dash light is readily detached and it may be taken to 90 any part of the car for investigating the source of trouble and when that has been found the finger catch may be engaged with any convenient part of the car or on the clothes of the person using the light in such 95 position that it throws light on the parts of the automobile needing attention.

The cable 10 is at all times under tension, the spring 16 tending to rotate the reel 11 so that the cable will be wound upon it. 100

What I claim is:

1. An electric lighting device of the kind described comprising an electric lamp detachably secured in a socket in a stationary element, means mounted on said element adjacent the socket and operatively connected with said lamp and with a source of current to provide electric current for the lamp while the latter is in its secured position on the stationary element or detached and removed some distance therefrom, said electric circuit comprising a cable having two 105 110

wires having their rear ends connected with the lamp and their forward ends connected with two concentric conductive rings in the flange of a reel mounted in a frame secured to the stationary element and said cable normally wound on the reel, two stationary electrodes each normally contacting with one of said rings and means for sending an electric current through said electrodes, said frame having an integral plug in which said electrodes are secured and said electrodes having their ends opposite from the reel exposed in the outer end of said plug and said means for sending an electric current through the electrodes comprising a cap

adapted to be oscillated and normally spring pressed against the end of said plug, and secondary electrodes in said cap comprising the ends of wires connected with a source of current and adapted to contact with the first mentioned electrodes when the cap is rocked, to control the circuit to the lamp. 20

2. The structure specified in claim 1, and means slidably mounted near the lamp and operatively connected with said cap to oscillate the latter for opening or closing the electric circuit. 25

In testimony whereof I affix my signature.

WILLIAM M. ANDERSON.
